PANEL MEMBER FOR A PRE-FABRICATED
BRIDGE

John Richard Johnson, London, England, assignor to
Thos. Storey (Engineers) Limited, London, England

Filed May 10, 1971, Ser. No. 142,105

Term of patent 14 years

Int. Cl. D25—02

U.S. Cl. D13—1 H

FIG. 1 is a top perspective view from one end and one side of a panel member for a pre-fabricated bridge showing my new design.

FIG. 2 is an elevational view of a panel member for a pre-fabricated bridge as FIG. 1 but from the other end.

FIG. 3 is an elevational view of a panel member for a pre-fabricated bridge as FIG. 1 but from the other side.

I claim:

The ornamental design for a panel member for a pre-fabricated bridge, as shown.
